United States Patent Office

Des. 188,721
Patented Aug. 30, 1960

188,721

CHAIR

Siegmund Werner, South Orange, N.J., assignor to Deeco,
Inc., Bloomfield, N.J., a corporation of New Jersey

Filed Dec. 4, 1958, Ser. No. 53,644

Term of patent 7 years

(Cl. D15—1)

The figure is a perspective view of a chair, showing my design. The side not shown is like the side shown while the back of the article is of conventional configuration.

I claim:

The ornamental design for a chair, as shown and described.
